STAND FOR TANKS

William R. Kepler, Wauwatosa, Wis., assignor to
 A. O. Smith Corporation, Milwaukee, Wis., a
 corporation of New York

Application September 15, 1937, Serial No. 163,877

4 Claims. (Cl. 214—113)

This invention relates to stands for supporting large tanks and is particularly applicable to the supporting of vitreous enamel lined beer storage tanks such as are disclosed in my Letters Patent No. 2,092,165 issued September 7th, 1937, for Supports for cylindrical vessels.

The enamel lining of these tanks is fired in a furnace at a temperature of about 1700° F., at which temperature the metal of the tank is fairly soft. In the firing operation the tank is placed onto a preheated transfer car and moved into the heated furnace and fired until the enamel lining is sufficiently fused. The car is then withdrawn from the furnace and the tank removed. This last step of removing the heated tank from the car without injuring the heated tank walls or fused lining presents quite a problem. It is the object of the present invention to facilitate the handling of the tank in loading it onto and removing it from the car.

An embodiment of the invention is illustrated in the accompanying drawing in which:

Figure 1 is a side elevation of a tank supported by the beam of a crane or other suitable hoisting device;

Fig. 2 is an end view of the disclosure of Figure 1, showing the tank supported upon a transfer car;

Fig. 3 is a vertical section of a supporting stand taken on the line 3—3 of Fig. 5;

Fig. 4 is a vertical section of a stand taken on the line 4—4 of Fig. 5; and

Fig. 5 is a top plan view of a stand.

As disclosed in my Letters Patent mentioned above, the tank 1 is provided at each head with a pair of supporting brackets 2. Each bracket has a horizontally disposed foot-plate 3 having a downwardly extending circular foot 4. The foot 4 has a socket 5 in its under side to be engaged by a hook 6 of a hoisting beam 7 supported by any suitable crane or derrick (not shown).

To permit the insertion of the hook 6 into the socket 5, a stand 8 is interposed between a supporting base 9 and the foot 4. This stand is preferably composed of an alloy metal capable of withstanding the heat of several firing operations so that it may be used a number of times. It is detachably secured to the foot-plate 3 by bolts 10 which pass through apertures in ears 11 and 12 of the stand.

The foot 4 engages a complementary socket 13 in the upper face of the stand and bears upon the base of the socket.

The stand has the shape of a hollow truncated cone having an inturned reinforcing flange 14 at its base and an enlarged head 15 to provide for the socket 13. The wall thickness of the stand is substantially uniform to avoid excessive stresses in cooling.

A vertical slot 16 is formed in the side wall of the stand to permit entrance of the hook 6 to the socket 5 into which the hook is guided by the upwardly tapering inner wall of the stand.

The stands are bolted onto the brackets 2 preparatory to hoisting of the tank and are positioned so as to present their slotted sides to their respective hooks 6 for easy engagement and disengagement thereby.

Various embodiments of the invention may be employed within the scope of the following claims.

I claim:

1. In combination, a stand for an object to be hoisted interposed between said object and a supporting base, said stand having a slot therein, and a hoisting hook to enter said slot and engage the underside of said object.

2. In combination, a stand for an object to be hoisted interposed between said object and a supporting base, said stand being of tubular structure and having a vertical slot in its wall, a hoisting hook to enter said slot and engage a socket in the underside of said object, and means within said stand to guide said hook into said socket.

3. In combination with a cylindrical tank to be hoisted, a bracket secured to said tank and having a socket in its underside, a tubular stand removably attached to said bracket and having a vertical slot in its side, a hook to enter said slot and means within said stand to guide the hook into said socket as the hook is raised.

4. In a support for a cylindrical tank to be hoisted, a bracket secured to said tank, and having a socket in its underside, a tubular stand removably attached to said bracket and having a vertical slot in its side to receive a hoisting hook for engagement with said socket.
